Patented Sept. 22, 1914.

UNITED STATES PATENT OFFICE.

GEORGE W. PAULI, OF BOSTON, MASSACHUSETTS.

HAND-BAG.

1,111,091.

Specification of Letters Patent.

Patented Sept. 22, 1914.

Application filed October 15, 1908. Serial No. 457,811.

To all whom it may concern:

Be it known that I, GEORGE W. PAULI, of Boston, in the county of Suffolk and State of Massachusetts, have invented certain new 5 and useful Improvements in Hand-Bags, of which the following is a specification.

This invention relates to hand bags, having particular reference to the type of bag known as wrist bags, and has for its object 10 to furnish a sufficiently capacious article of this character which may be folded into a small compass when empty.

A further object is to provide such a bag with a device capable of being folded with 15 the bag and of holding the bottom thereof extended in a flat condition when opened to its fullest capacity, such device being also adapted to prevent the central part of the bag bottom from bulging downward.

20 Still another object is to enable the lower portion of the bag to be doubled and retained in that condition when empty so as to diminish the apparent depth of the bag and make the same more convenient to 25 carry.

Of the accompanying drawings,—Figure 1 represents a side elevation of a bag embodying the principles of my invention. Fig. 2 represents an end elevation of the 30 same when opened and distended to its fullest capacity. Fig. 3 represents a sectional view of the bottom of the bag distended, showing the relation of the distending and stiffening device. Fig. 4 represents an end 35 elevation of the bag when folded into its thinnest compass. Fig. 5 represents a similar view, showing the bag further folded to diminish its apparent depth. Fig. 6 represents a perspective view of a stiffening 40 frame adapted to be used with the bag for holding the bottom in an extended flat condition. Fig. 7 represents a detail view of a portion of this frame, illustrating the hinge and the stop by which the frame is 45 prevented from being folded or doubled except in one direction.

The same reference characters indicate the same parts in all the figures.

Referring to the drawings, the body of 50 the bag or bag material as a whole is represented by a and consists of the sides a' , bottom a^2 and ends a^3 , these members being united together in any convenient manner so as to form a complete bag. The upper 55 edges of the bag material are united to the

usual hinged clasp frame consisting of the members b' and b^2 pivoted together at b^3 and having hooks b^4 and a catch b^5 of any usual or approved form and construction.

The ends of the bag material are creased 60 on the lines $c c' c^2 c^3$ and c^4 , and the bottom is creased longitudinally at its center so as to enable both ends and bottom to be folded inwardly to permit the flat sides a' to be brought together in substantial parallelism 65 when the bag is closed, as represented in Fig. 4. The bag is capable of being still further folded between its top and bottom on a longitudinal line, represented at d in Fig. 1, this fold being located so that the 70 bottom of the bag is brought upward when folded beneath a flap e . On this flap are fastening devices f which coöperate with complementary fastening devices g on the side of the bag which, when the latter is extended, is opposite to the flap. As may be seen from Figs. 4 and 5, these fastening devices are brought into coöperation when the bag is doubled about the fold d . Any appropriate and convenient form of fastening 75 device may be used, that here shown consisting of plug and socket members, the fastener f having a bulging projection f' adapted to enter a socket in the corresponding member g .

In order to hold the bottom a^2 of the bag out flat when the same is distended to its fullest capacity, I provide an expander or distender h . This expander is preferably made of stout wire having sufficient rigidity 80 for the desired purpose, formed into a rectangular frame consisting of two parts held together by a rod or pintle h' , although in lieu of this construction it is permissible to make the distender of two flat leaves hinged 85 together. The distender has two outer side elements h^2 and h^3 which swing pivotally about the pivot member h' and lie within the edge folds h and h' of the bag. When the bag bottom and distender are spread out, 90 they are of approximately equal area and the elements h^2 h^3 hold the bottom edges of the bag apart and stretch the bottom a^2 into an approximately flat condition. This distender holds the bottom of the bag expanded 95 to its fullest extent while articles are being placed in it, and it is also constructed so as to prevent the bottom of the bag from bulging downward under the weight of the contents, and allowing the sides to press upon 100

85

such contents to the possible injury thereof. The distender also improves the appearance of the bag by keeping the bottom edges straight and preventing the sides from being 5 bent inward.

When the distending device is constructed of wire, as illustrated herein, the elements h^2 and h^3 are provided with end members which are bent at right angles, and the ends 10 of which are wrapped about the pintle h' . The ends h^4 of one of the members are carried beyond the pintle and bent across the end portions of the other member h^3 , as 15 shown in Figs. 6 and 7. These bent or hooked ends h^4 lie above the member h^3 so as to prevent the pivot rod and center of the frame being depressed below the plane of their outer elements. This form of stop enables the frame to be bent upward and the 20 pivot rod to be carried up with the central fold of the bag bottom when the latter is folded, but prevents any further movement of the center of the frame after the same has been brought into the plane of the 25 extended bottom of the bag. By means of these stops, the weight of the contents of the bag is supported and is prevented from causing the bag to bulge at its bottom, as previously stated.

30 The distending device is placed within the bag and is attached to the bottom thereof by any convenient and suitable means, as by loops of the bag material or by being sewed in place. The hinged rod h' lies along and 35 above the longitudinal fold of the bottom and rises with this fold when the bottom is doubled upon itself to diminish the thickness of the bag. If desired, the distending device may be provided with a spring to assist in this folding action, and such spring 40

may be caused to fold the bag automatically when the same is empty.

I claim:

1. A hand-bag having flat sides and centrally creased ends and bottom, combined with a skeleton wire frame having sides connected with the side edges of said bottom, and a hinged pintle rod at the crease of said bottom, whereby to permit folding of the bag and to distend the bottom thereof when 50 the same is expanded.

2. A hand-bag having a folding bottom and ends whereby the sides may be brought together, and a folding wire skeleton stiffener contained within the bottom of the bag, 55 for spreading the bottom out flat when opened, said stiffener being provided with a pintle and a finger on one of the members overlying the other member to form a stop to prevent depression of its central portion 60 below the plane which it occupies when opened.

3. The combination with a hand-bag having a folding bottom and ends, of a stiffener frame having the outline of the said bottom 65 when such bottom is spread out, said frame being of wire skeleton construction and consisting of a pintle and two frame members having eyes pivotally mounted upon said pintle, one of said members having its end 70 wrapped about the pintle and carried over the adjacent part of the other member in position to form a stop when the members are in the same plane.

In testimony whereof I have affixed my 75 signature, in presence of two witnesses.

GEORGE W. PAULI.

Witnesses:

ARTHUR H. BROWN,
P. W. PEZZETTI.
